UNITED STATES PATENT OFFICE,

HIAL S. GRANNIS, OF SOUTHBURG, CONNECTICUT, ASSIGNOR TO THE PECK, STOW & WILCOX COMPANY, OF SAME PLACE.

STOVE-PIPE FORMER.

SPECIFICATION forming part of Letters Patent No. 402,582, dated May 7, 1889.

Application filed February 6, 1889. Serial No. 298,893. (No model.)

To all whom it may concern:

Be it known that I, HIAL S. GRANNIS, a citizen of the United States, residing at Southbury, in the county of Hartford and State of Connecticut, have invented certain new and useful Improvements in Stove-Pipe Formers, of which the following is a specification.

My invention relates to improvements in stove-pipe formers; and the principal object 10 of my invention is to provide convenient and efficient means for releasing and tipping the roller around which the pipe is formed, so that the pipe may be slipped endwise off the roller, thereby making what is called a "slip-roll 15 former."

In the accompanying drawings, Figure 1 is a front elevation of my former with the middle portion broken away. Fig. 2 is a side elevation of the right-hand end. Fig. 3 is a side 20 elevation of the left-hand end with the hinged box thrown backward and the upper roller tilted. Fig. 4 is a perspective view of the upper end of the frame for the right-hand end of the former. Fig. 5 is a vertical section on line $x-x$, Fig. 3, of the right-hand end of 25 said former, some of the parts being shown in elevation. Fig. 6 is a side elevation showing the outer side of the box for the upper roller at the right-hand end of the machine; 30 and Fig. 7 is a transverse section, on line $y-y$ of Fig. 3, of the hinged box for the upper roller at the left-hand end of the machine.

A designates the frame for the right-hand end of the machine, and B the frame for the 35 left-hand end of the machine.

C designates the upper roller, and D D the lower rollers, while E designates the tie-rod which holds the two end frames in place. The two lower rollers, D D, are adjusted to and 40 from the upper roller by means of the adjusting-screws 8, which bear against the under side of the sliding boxes 9, in which said rollers take their bearings.

At the left-hand end of the machine the 45 upper roller takes its bearing in the recess 10, Fig. 7, of the hinged box 11, said bearing-recess being indicated by broken lines in Fig. 3. This hinged box is hung upon the frame B by any suitable hinge, as at 12, Fig. 3, while 50 its outer end is slotted and provided with a pivotal link or strap, 13, to the other end of

which link is pivoted the cam-lever 14. At the front part of the frame B is a projecting lug, 15, which is slotted vertically to receive the body of the link 13. When the hinged 55 box 11 is brought down over the journal at that end of the upper roller, C, and the cam-lever is held in substantially a horizontal position, the lower end of the link 13 may be slipped into the slot in the slotted lug 15, af- 60 ter which by depressing said cam-lever into a vertical position, as shown in Fig. 2, the hinged box is firmly drawn down and secured in place. By reversing the operation the hinged box is released again and may be 65 turned backward on its hinge, as shown in Fig. 3, thereby releasing that end of the upper roller.

While I prefer to slot the lug 15 so that the link or strap 13 shall be received in the slot 70 thereof and the cams upon both sides of said strap bear upon said lug, this is not essential, as the parts would operate the same if all that portion of the lug on one side of its slot were removed, in which case the cam 14 would be 75 held by a lug at one side only of the link 13.

At the right-hand end of the machine one of the lower rollers, D, is provided with an ordinary driving-crank, F, and a pinion, G, which meshes into a like pinion, H, on the 80 upper roller, C. The right-hand end of said roller is provided with a shaft-like projection, 16, in which is formed a peripheral groove, 17. The frame A is provided with a horn or rigid projection, 18, which extends over the shaft- 85 like projection 16 of the upper roller, and its inner face is formed with a bead, 19, fitted to the groove 17, which bead forms the fulcrum or central point upon which the upper roller, C, may be tilted. The upper roller, C, at this 90 end of the machine has its bearing in the box 20, which box is provided with side ledges, 21, for bearing upon the fixed ledges 22 of the frame A at the respective sides of the recess that receives said box. These ledges 22 pro- 95 ject slightly from the inner face of the frame A and are curved toward their upper end on the arc of a circle whose center is the bead or fulcrum 19, on which the roller C is tilted. The confronting faces of the ledges 21 are 100 formed on a corresponding curve, as shown in Fig. 1. The box 20 is lifted and let down by

means of the lifting-screw 23, upon the squared upper end of which screw is placed a wrench, 24, for convenience of turning said screw. This screw is connected with the box in such manner as to allow freedom of the box to rock or tilt thereon. I have illustrated the screw as connected with the box by means of a knob, 25, at its lower end, which knob takes into a transverse recess, 26, having overhanging shoulders in the boxes. (See Figs. 5 and 6.) This particular connection of the box and lifting-screw is made the subject of a separate application, Serial No. 298,895, of even date herewith.

15 It is only essential to my present invention that the lifting-screw 23 and box 20 be connected by some means that will permit of the rocking motion of said box. I also provide the upper end of the frame A with two lugs, 20 27, to limit the movement of the wrench 24 to half a turn. These lugs are not essential, but are a matter of convenience, as they are intended to limit the movement of the wrench to that half-circle which is outside of the frame, and consequently the wrench will not be brought over the body of the rollers, so as to be in the way of the work being formed thereon. A half-revolution of the lifting-screw 25 is ample for the purposes of my invention. 30 The lifting-screw 23 and the box 20 are so adjusted that when the wrench 24 is carried around against the rear one of the lugs 27 that end of the roller will be in proper position for use and will coincide substantially with the 35 opposite end of the roller as held in place by the hinged box 11. Said box 11 and the rigid horn 18 render the upper roller, C, non-adjustable by fixing the height for the working position of said roller. When in this position, 40 the lower rollers will be adjusted to the upper roller for the work desired. After a pipe has been formed on said rollers the hinged box is turned backward on its hinge and the wrench-handle brought around toward the front to 45 lift the box 20, thereby lifting also the roller C, causing it to tilt or swing upon its fulcrum-bead 19, so as to elevate the left-hand end, as shown in Figs. 3 and 5, sufficiently to enable the pipe to be slipped off from said upper 50 roller. The wrench 24 is then turned back again to its rearmost position and the hinged box again secured over the left-hand end of the upper roller, and the machine is ready for forming another pipe.

55 The class of slip-roller formers to which my invention relates is an old one, and one prior patent in this class shows a box for one end of the upper roller as made of two parts adjustable to and from each other and secured

for being adjusted vertically together in a 60 hinged yoke that swings on an axis extending transversely to said upper roller, while the opposite end of said upper roller is mounted in a hinged bearing adjustable vertically in the frame by an adjusting-screw, said hinged bearing forming the axis of said upper roller for tilting it. Said upper roller is also extended beyond its hinged bearing in a shaft-like projection to a third vertically-adjustable bearing for the purpose of preventing the 70 opposite end of the roller from falling when the bearing in the hinged yoke is removed therefrom. The two lower rollers in said machine are non-adjustable. All of said prior art is hereby disclaimed. 75

I claim as my invention—

1. The combination of the non-adjustable upper roller, C, hinged box 11, for holding and releasing one end of said roller, mechanism for tilting said roller, and two under rollers 80 provided with adjusting-screws 8, for adjusting said under rollers relatively to the upper tilting roller, substantially as described, and for the purpose specified.
2. The combination, in a former, of the 85 hinged box 11, the upper roller, C, provided with a shaft-like projection having a peripheral groove, 17, the rigid horn 18 upon the frame, provided with a fulcrum-bead for said shaft-like projection, the box 20, and lifting-screw 23, for lifting said roller and swinging it on its fulcrum at the end of the rigid horn 18, substantially as described, and for the purpose specified.
3. In a former having an upper tilting roller, 95 the combination of the frame B, provided with the lug 15, the hinged box 11, for holding one end of said upper roller, the link 13, hinged to the outer end of said box, and the cam-lever 14, substantially as described, and 100 for the purpose specified.
4. In a former having an upper tilting roller provided with a shaft-like projection having the peripheral groove 17, the frame B, having the horn 18 and fulcrum-bead 19, fitted 105 to said groove 17, the projecting ledges 22, also formed on said frame, and the box 20 and lifting-screw connected thereto, said box 20 being provided with side ledges, the faces of which, together with the faces of the ledges 110 22, are on the arc of a circle of which the fulcrum-bead 19 is the center, substantially as described, and for the purpose specified.
